UNITED STATES PATENT OFFICE.

NORMAN W. NUTT, OF TRENTON, NEW JERSEY.

INCANDESCENT-ELECTRIC-LAMP SOCKET.

1,366,702.

Specification of Letters Patent. Patented Jan. 25, 1921.

Application filed August 1, 1919. Serial No. 314,694.

To all whom it may concern:

Be it known that I, NORMAN W. NUTT, a citizen of the United States, residing in Trenton, in the county of Mercer and State 5 of New Jersey, have invented a new and useful Improvement in Incandescent-Electric-Lamp Sockets, of which the following is a specification.

My improvement relates to such lamp 10 sockets of the keyless type and has for its object the production of an efficient and safe socket of very simple form and few parts, resulting in reduction of cost in manufacture.

15 In the accompanying drawings, forming a part of this specification, Figure 1 shows a vertical diametrical section of my device taken on the line 1—1 in Fig. 3; Fig. 2 shows a similar section taken on the line 20 2—2 in Fig. 3; Fig. 3 is a top view of my socket with the metal cap removed; and Fig. 4 is a view of the under side of the metal cap, showing the insulating lining thereof and the means for fastening it to 25 the cap.

The body, *a*, of my socket is made preferably of porcelain. Its upper face is recessed slightly within a marginal circular bead, *b*, and has die-formed depressions, *c* 30 and *d*, to receive the binding screws and plates *e* and *f*, respectively. Through a central opening in the body *a* is passed the screw *g*, which electrically connects the plate of the binding screw *e* with the central 35 spring lamp-contact *h*. The metal screw-socket, *i*, adapted to receive the threaded base of a lamp, is open at both ends, save for the flanges, *k*, *k*, at its upper or inner end. Said flanges are pierced to receive 40 the screws *l* and *m*, respectively. Passing through the body *a*, the screw *l* establishes electrical connection between the plate of the binding screw *f* and the screw-socket *i* and aids in holding the screw-socket to the 45 body *a*. The screw *m* is screwed into a small metal plate *o* lying in a recess in the upper face of the body *a* and aids in holding the screw-socket *i* to its place in the body *a*.

50 The cap, *p*, of the socket is of metal, having centrally located therein an aperture of oval form (indicated by dotted lines in Fig. 4) to receive the annular internally-threaded nipple, *q*, adapted to connect with the 55 current-wire conduit, bracket or fixture. The nipple *q* is entered to the oval aperture

in the cap *p* and is swaged therein into conformity with said oval aperture, a firm union of the two elements being thus effected. Upon the inner face of the cap *p* 60 is fixed a flat insulating member, *r*, of flexible material, having a central aperture of less diameter than the diameter of the nipple *q* for the passage therethrough of the current wires. This insulating member is 65 attached firmly to the cap *p* by eyelets, *s*, *s*, which are passed through small circular openings in the cap and insulating member and are clamped thereon. The cap *p* is also pierced at *t*, *t* to receive the screws *u*, *u* 70 which pass through openings in the body *a*, and hold the cap thereto.

By the described construction I produce a unitary body or insulating base for the socket, reduce the metal parts to the smallest practicable number and sizes, and provide ample security against short-circuiting in a simple structure which is readily assembled.

Having thus described my invention, I 80 claim:

1. An incandescent electric lamp socket having a unitary body portion of insulating material containing a metal screw-socket to receive the base of a lamp, and conducting 85 means, including a central lamp contact, the upper face of said socket provided with an upstanding marginal flange forming a recess, in combination with a metal cap having an oval aperture therein and an annular 90 threaded nipple swaged into said aperture adapted to seat on said flange; and insulated means interposed between said metal cap and said unitary body, said insulating means being clamped between the cap and 95 body in said recess.

2. An incandescent electric lamp socket having a unitary body of insulating material, the upper face of said body being provided with an upstanding marginal flange 100 forming a recess, and a metal cap secured to said unitary body, said metal cap having a threaded nipple and a flat sheet of insulating material attached to the inner face of the cap by eyelets clamping it thereto, and covering the exposed portion of said cap and the inner end of said nipple, said cap resting on the marginal flange and the insulating material seated within said recess.

3. An incandescent electric lamp socket having a unitary body of insulating mate-

rial recessed at one end to receive a screw-socket for a lamp and at the other end having separated recesses to receive binding-screws and plates and the current-wires connected therewith, in combination with an insulated metal cap having a central aperture therein and a threaded nipple swaged therein, screws passing through the upper portion of said body and holding said metal cap thereto, a screw connecting one of said binding-screws and its plate with said lamp

5

10

screw-socket, and a screw connecting the other of said binding-screws and its plate with a central lamp-contact, both of said latter screws passing through the partition 15 formed between the upper and lower recesses of said body.

NORMAN W. NUTT.
